[57] **CLAIM**

The ornamental design for the hair trimmer, as shown and described.

DESCRIPTION

FIG. 1 is a front perspective view of the hair trimmer of the present invention.

FIG. 2 is a top plan view of the hair trimmer of FIG. 1.

FIG. 3 is a bottom plan view of the hair trimmer of FIG. 1.

FIG. 4 is a left side elevational view of the hair trimmer of FIG. 1, which also illustrates the identical right side elevational view of the hair trimmer of FIG. 1.

FIG. 5 is a front elevational view of the hair trimmer of FIG. 1.

FIG. 6 is a rear elevational view of the hair trimmer of FIG. 1; and,

FIG. 7 is a rear elevational view of a second modified embodiment, the sides not shown being identical to the first disclosed embodiment.
